(57) **CLAIM**

The ornamental design for a suction probe apparatus, as shown and described.

DESCRIPTION

FIG. 1 is an isometric view of a suction probe apparatus; FIG. 2 is a top plan view thereof;

FIG. 3 is a bottom plan view thereof;

FIG. 4 is a right side elevation view thereof;

FIG. 5 is a left side elevation view thereof;

FIG. 6 is a rear, end, elevation view thereof;

FIG. 7 is front, end, elevation view thereof;

FIG. 8 is a cross-sectional view thereof taken along line 8-8 of FIG. 2; and,

FIG. 9 is a cross-sectional view thereof taken along 9-9 of FIG. 2.

The broken lines shown in FIGS. 1-9 illustrate portions of the suction probe apparatus that form no part of the claimed design.

1 Claim, 6 Drawing Sheets
